UNITED STATES PATENT OFFICE.

LUKE MESSIER, OF ALBANY, NEW YORK, ASSIGNOR OF ONE-HALF TO
JAMES M. DAVIS, OF SAME PLACE.

HOISTING AND CONVEYING MACHINE.

SPECIFICATION forming part of Letters Patent No. 237,571, dated February 8, 1881.

Application filed November 26, 1880. (No model.)

To all whom it may concern:

Be it known that I, LUKE MESSIER, of the city and county of Albany, and State of New York, have invented certain new and useful 5 Improvements in Hoisting and Conveying Apparatus, of which the following is a full and exact description.

My invention relates to improvements in apparatus for hoisting coal or other substances 10 and conveying it to a limited distance from the point of hoisting, but more especially to that class of devices that are used upon wharves for unloading coal and ore from vessels and depositing such loads in piles on the wharf; 15 and the objects of my improvements are, first, to provide a machine that may be moved sideways, as an entirety, on tracks arranged transversely to the line of the conveying-tracks, to increase the width of the piles of the deposited 20 material; second, to effect, by means of a single hoisting-chain, the reciprocal hoisting and lowering of the buckets at opposite sides of the machine; third, to afford facilities for properly adjusting the length of the pendent 25 ends of the hoisting-chain to the varying requirements of the work; and, fourth, to automatically secure the traveling carriage in place to receive the hoisting-bucket, to lock the bucket fast in the carriage, and to automatically 30 effect the release of those parts at the required times. These objects I attain by means of the mechanism illustrated in the accompanying drawings, which form a part of this specification, and in which—

35 Figures 1, 2, and 3 are respectively a side elevation, a front elevation, and a plan view of my invention, and in each of said figures portions of the frame-work are broken away for the purpose of condensing the figures and 40 exposing some of the underlying parts. Figs. 4 and 5 are enlarged and detached views of the drum-shaft and its attached and connected appliances; Fig. 6, an enlarged front view of the mechanism for adjusting the pendent ends 45 of the hoisting-chain. Figs. 7, 8, 9, and 10 are enlarged views of the traveling carriage and its details; and Figs. 11 and 12 are enlarged details of the construction of the hoisting-bucket.

50 As represented in the drawings, A is the frame-work or tower of the machine, having at its top a forward extension, A', whereby the

hoisting mechanism is projected beyond the line of the base of the tower and the device adapted for hoisting loads from a vessel lying 55 beside a wharf. The frame-work A is rendered movable sideways by means of the flanged wheels a, which are fixed to the frame-work, and are adapted to run on the tramways a'. It is also provided with platforms or landings a², for containing the motive power and other machinery required for operating the apparatus. As preferably constructed, the lower platform contains the motive power. The second one contains a driving-shaft, B, adapted 60 to rotate in either direction, as occasion requires, and on the upper one the drums and other appliances for operating the hoisting and conveying mechanisms are placed.

The drum-shaft C is formed of two separate 70 lengths, ranged in line with each other, and having a spring, c, interposed between the adjacent ends thereof, for the purpose of forcing apart the two sections. The belt-drum D is placed on the shaft C in such manner that it 75 will cover the joint of the two parts of said shaft, and it is fitted loosely thereon, so that the shaft may revolve freely without imparting motion to the drum. At each end of said drum a friction-V is formed, that will engage 80 at the required times with friction-clutches D', secured to and revolving with the two sections of the shaft C. The said friction-clutches are forced into contact with the friction-V's of the drum by sliding the two parts of the shaft C 85 toward each other by means of the hand-lever E, which is connected by the rods e² to the levers e, provided with adjustable centers e', which bear against the outer ends of the shaft C. The lever E is also connected, by 90 means of suitable ropes or chains, f, which pass over the sheaves f', to the brake-levers F, for controlling the brakes F', which bear against the periphery of the drum D, the parts being arranged to operate reciprocally— 95 that is to say, when the lever E is moved to force the two pieces of the shaft C together and carry the friction-clutches into gear, the cords f elevate the outer ends of the levers F, to raise the brakes F' clear from the drum D; 100 but when the lever E is moved back by the spring c spreading apart the two parts of the shaft C the springs f² will draw down the outer ends of the levers F and cause the brakes

F' to close against the drum D to keep it from revolving.

On the shaft C, near each of its outer ends, are the drums G, for operating the ropes by which the conveying mechanism is moved. Said drums are fitted to permit the shaft to revolve freely in them, and each is provided with a friction-V, that is fitted to engage with its proper friction-clutch G' of the pair of said 10 clutches adapted to slide on splines fixed in the shaft C. Forked levers g, provided with the usual studs for engaging in the grooved hubs of the friction-clutches G', are employed for sliding said clutches into and out of gear 15 with the drums, and each of the forked levers g is connected to a brake-lever, g', for the purpose of operating brakes g'', that bear against the drums G, the arrangement and mode of operating said brakes being identical with 20 that of the same devices for the drum D, as hereinbefore described. A further description is unnecessary. Motion is imparted to the shaft C from the shaft B by means of the pulleys b and b² and belts b'. The lever E, when 25 moved into position to hold the friction-clutches D' in gear with the drum D, has its outer end retained in place by the spring-latch e³, and under the like conditions the spring-latches g³ perform the same functions for the 30 levers g.

The hoisting-shaft H revolves in bearings fixed on top of the frame-work A, and is driven by the belt I, that runs from the belt-drum D to a drum, h, secured to said shaft. At the 35 outer end of the hoisting-shaft a sprocket-wheel, h', is secured, for the purpose of imparting motion to the hoisting-chain J, which engages with the horns of the wheel on its under side, and from thence passes over the tops of the sheaves K. By this arrangement the part 40 of the hoisting-chain that passes around the under side of the sprocket-wheel is drawn by the weights suspended by the chain closely against the under side of the wheel, thereby giving to the horns thereon a secure hold of the hoisting-chain. After passing over the 45 sheaves K the ends of the hoisting-chain J pass directly down, (through opening in the tracks A², as shown in Fig. 6,) and are provided with hoisting-hooks j. The sheaves K 50 revolve in bearings secured to the cross-beams K', which are adapted to move vertically on the guides k, fixed to the top of the forward extension, A'. The pendent pieces k' are secured to the cross-beams, K' and are provided with toothed racks, which gear into pinions secured on the transverse shaft k², and by this arrangement the cross-beams K', with the sheaves K, can be raised or lowered as occasion 55 requires, to adjust the pendent ends of the hoisting-chain to the length required for unloading boats that are affected by the tides, variations in draft of water, &c.

Near the middle of the hoisting-shaft H 60 there is a drum, h², on which the two ends of the rope h³ are wound in opposite directions, and the bight of said rope passes under the sheave

h⁴ near the bottom of the tower A. Attached to the two parts of the rope h³ that lead from the drum h² to the sheave h⁴ are buttons or stops h⁵, arranged at such points on said rope that when either pendent end of the hoisting-chain J is raised to the height required the button on the part of the rope h³ that is moving in the same direction with the rising part 75 of the hoisting-chain will engage with and raise the outer end of the bifurcated lever h⁶, to the inner end of which is attached the pendant rod h⁷, that bears upon the upper edge of the spring-latch e², and the movement just 80 described of the lever h⁶ depresses the spring-latch and effects the release of the lever E, thereby disengaging the friction-clutches D' and applying the brakes F to stop the rotations of the drum D, in the manner herein- 85 before described.

Two longitudinal tracks, A², are secured beneath the upper part of the frame-work A. The rearmost ends of said tracks are supported by an elevated transverse track, A³, on which 90 they are adapted to move sidewise, to conform to the same movement of the tower A. On each of said longitudinal tracks there is placed a traveling carriage, L, arranged to move back and forth thereon, for the purpose of conveying the raised loads of material rearward. Each of said carriages is provided with truck-wheels l, arranged to run on the lower flanges of the tracks A², so as to suspend the automatic mechanism of the carriage below said tracks. This 95 automatic mechanism consists of a tumbling-shaft, L', to which are secured, to one of its projecting ends, a grooved segment or wheel, l', for the operating-ropes hereinafter described, to the opposite end a spiral cam, l'', and between the hanging side pieces of the carriage the arms l³. The latter are connected by jointed links to the hooked arms l⁴, pivoted to the side pieces of the carriage, and so arranged in relation to the slotted openings L² in the said 100 side pieces that the hooked ends, when depressed, as shown in Fig. 7, will swing clear from said openings, but when raised, as shown in Fig. 8, will close across the openings, so as to engage under the bail of a bucket, herein- 105 after described. Each carriage and its contained mechanism is operated by the ropes M and M', (one of each being required to operate each carriage,) which are arranged as follows: The rope M has one of its ends secured to one point of the segment l', as shown in Fig. 7, and from thence runs forward around a sheave, N, and thence passes backward over one of the double-grooved sheaves O, (which 110 revolve on the stationary shaft O'), and from thence passes downward and is wound on its proper drum G. The rope M' has one of its ends secured to the point of the segment l' that is opposite to the one to which the rope M is attached, and from thence backward and 115 over the sheave N', fixed to the rearmost end of the tracks A², then forward over the sheave O, and from thence downward to its 120 drum G, upon which it is wound in a re- 125

versed direction to the rope M, so that when the drum is rotated to wind up either of said ropes the other one is reciprocally unwound. The arrangement of said ropes at the opposite sides of the machine, after passing over the sheaves O, is as follows: At one side they lead down from the sheave to corresponding sides of the drum G, as shown by the dotted lines in Fig. 1; but at the other side of the machine they are crossed, as shown by the full lines in the same figure, to lead to the opposite sides of the drum G. By this arrangement of the ropes, when the two drums G are revolving in the same direction, the two carriages L will move in contrary directions, so as to carry an empty bucket forward and a loaded one rearward. Each carriage L, while at rest at the forward end of its track A², is locked in place by means of a spring-latch, l⁵, pivoted to the side of the carriage, and adapted to engage on a stationary catch-piece, P, secured to the framing of the forward extension, A'. On turning the drum G to wind up the rope M' (while the carriage is locked fast) the first movement of said rope causes the segment l' to turn the shaft L', so as to draw up the hooked arms l⁴ across the slotted openings L² and carry the point of the cam l² upward to raise the spring-latch l⁵, as shown in Fig. 8, and release the carriage L. In effecting this unlocking movement the segment l' is turned until its stud q engages with the shoulder q' of the spring-latch Q and locks the shaft L' and its attached parts in the positions indicated by the dotted lines in Fig. 7. The continued motion of the rope M' then draws the carriage L backward on its track A² to any point at which the load is to be dumped. On reversing the motion of the shaft C the rope M is wound up to draw the carriage L forward until it reaches the front end of its track, where the outer end of the spring-latch Q engages under the beveled end of the cam-piece Q', fixed to the framing of the forward extension A', whereby the opposite end of the spring-latch is raised to release its shoulder q' from the stud q on the segment l', after which the continued movement of the rope M causes the shaft L' to turn, so as to move the point of the cam l² downward, to release its control over the spring-latch l⁵, and permitting the hook of said spring-latch to engage with its catch-piece P, and at the same time the hooked arms l⁴ drop down into the position shown by the full lines in Fig. 7. When the segment l' has by its movement completed the operations just described, a stud, r, on the side of the segment engages with a hanging arm, R, to move the rod r' and bell-crank r², to depress the pendent rod r³, so that it will release the spring-latch g³ from its hold on the lever g, that controls the drum G, by which the movements of the carriage are at that time governed, and thereby the movement of the ropes at that side of the machine is stopped.

The bucket S is provided with bottom sections, S', that are hinged thereto so as to open in the middle and swing downward, as shown in Fig. 11. Springs T are connected to the bottom sections, for the purpose of drawing them up to close the bottom of the bucket, and when closed the bottom sections are locked in place by the spring-catches U, pivoted to the sides of the bucket and provided with hooks that engage under the lips s of the bottom sections.

The bail V, rigidly fixed to the top of the bucket S, is provided at its apex with an open standing loop, v, for engaging on the hooks j of the hoisting-chain; and it is also provided with slides W, or any equivalent mechanism, for depressing the sliding pieces X—against the resistance of the springs x—to which the spring-catches U are connected by the links u. The disengagement of the spring-catches from the bottom sections, S'—while the bucket is suspended from the hooked arms l⁴ of the traveling carriage—is effected by means of a pointed slide, Y, attached to the carriage L, and having its point arranged to enter between the adjacent ends of the slides W, so that as the slide Y is forced inward until its widened part will spread apart the slides W and force the spring-catches U back into the positions shown by the dotted lines in Fig. 11, the bottom sections, S', are thereby released, so that the weight of the load contained in the bucket will force open the bottom sections to permit the load to fall out of the bucket. The pointed slide Y is moved to effect the operation just described by its projecting end y striking one of the knee-pieces Z, that are adjustably attached to the tracks A² at any point where at the time it is desired to have the bucket-loads dumped. At the beginning of the forward movement of the carriage L the spring y' retracts the slide Y from between the slides W, thereby permitting the parts to return to their positions, so that the spring-catches U can again secure the bottom sections.

The operation of my apparatus is as follows: While the drum-shaft C is revolving in either direction, the lever E is moved (and locked by the spring-latch e³) to force the friction-clutches D' into contact with the drum D, whereby a rotatory motion corresponding in direction to that of the shaft C is imparted to the hoisting-shaft H, to move the hoisting-chain J to raise the loaded bucket and lower the empty one, that are then attached to the hooks j on the opposite ends of said chain. When the end of the chain that bears the loaded bucket is raised to a sufficient height, the bail V passes into the slotted opening of the carriage on that side of the machine, and is raised therein to a position where the hooked arms l⁴ can readily engage beneath said bail. When this position is attained the button h⁵ on the rising part of the rope h³ strikes the end of the bifurcated lever h⁶, to trip the spring-latch e³ and disengage the lever E, whereupon the motion of the drum D and shaft H is instantly stopped, as hereinbefore described. The shaft C continues its rotations in the same direction, and the fric-

tion-clutch G'—on the side of the machine where the loaded bucket is suspended—is moved into gear with its drum G, setting said drum in motion to wind up its rope M', whereby the 5 segment l' is turned to raise the hooked arms l' to engage under the bail of the bucket and lift said bucket clear from the hook of the hoisting-chain. When this is accomplished the segment l' is locked in position by the spring- 10 latch Q, and the spring-latch l' is raised to release the carriage L. The continued movement of the rope M' then draws the carriage with its loaded bucket backward until the projecting end of the slide Y strikes the knee-piece Z and effects the dumping of the load from the bucket, as hereinbefore described. Then the drum G must immediately be rotated in the contrary direction to draw the carriage and empty bucket forward until the former 15 has reached its place at the end of the forward extension, A', where the outer end of the spring-latch Q engages under the cam-piece Q' and releases the segment l', so that the shaft L' will turn to set free the spring-latch l'—to lock the 20 carriage—and let the hooked arms l' dropdown, to permit the bail of the bucket to re-engage with the hook of the hoisting-chain. Just as the segment l' has completed its last-described act (turning the shaft L') the stud r on its side eng- 25 gages with the hanging arm R, thereby causing said arm to move and, through the intermediate mechanism hereinbefore described, depress the pendent rod r², to disengage the spring-latch g³ from the lever G and stop the rotations of the drum G at that side of the 30 machine. As soon as the last-described action has been accomplished, and without changing the direction of the rotations of the drum-shaft C, the lever E should be moved to throw the friction-clutches D' into gear with the drum D, 35 whereby the shaft H is rotated in the proper direction to lower the emptied bucket, and at the same time hoist a loaded bucket at the opposite side of the machine. Then, by a repetition 40 of the operations above described, the load in the bucket last raised is conveyed rearward and dumped.

When a sufficient quantity of material is deposited along the line of the longitudinal tracks A², or when it is required to form piles of different materials, the machine may be moved sidewise on the tramways a'.

I claim as my invention—

1. In a hoisting and conveying machine, the tower or frame-work A, provided with rigid longitudinal conveying-tracks A², adapted to move as an entirety on the tramways a' and elevated track A³, as and for the purpose herein specified.
2. In a hoisting-machine, the hoisting-shaft H, adapted to rotate in opposite directions, and provided with a sprocket-wheel, h', and the sheaves K, in combination with the hoisting-chain J, arranged in relation to the said sprocket-wheel and sheaves as herein described, the opposite ends of said hoisting-chain being pendent from the sheaves K and

provided with hooks j, all arranged to operate as herein specified.

3. The combination, with the hoisting-shaft H, rotating in fixed bearings, and provided with the sprocket-wheel h', and the hoisting-chain J, of the sheaves K, adapted to adjust vertically in relation to the hoisting-shaft H, substantially as and for the purpose specified. 75

4. The combination, with the drum-shaft C, composed of two separate lengths ranged in line, and having a spring, e, interposed between their adjacent ends, said shaft being provided with a loose drum, D, and the fixed 80 friction-clutches D', of the levers E and e and the rods e', all arranged to operate as herein specified.

5. In a traveling carriage for a hoisting and conveying machine, the tumbling-shaft L', for 85 operating the hooked arms l', as described, and having a segment or wheel, l', and a cam, l', secured thereto, in combination with the spring-latches l' and Q, as and for the purpose specified. 90

6. The combination herein described of one or more of each of the drums G, tracks A², traveling carriages L, ropes M and M', and sheaves, N N', and Q, all arranged to operate as specified. 95

7. In a hoisting and conveying machine, the automatic mechanism herein described for detaching the bucket from the hoisting-chain and locking said bucket in the traveling carriage, and consisting of the tumbling-shaft L', adapted 100 to operate the hooked arms l', as described, and provided with a segment or wheel, l', having a stud, q, arranged to co-operate with the spring-latch Q, as herein specified. 105

8. The bucket S, provided with bottom sections, S', arranged to close by means of the springs T, and secured by the spring-catches U, the rigid bail V of said bucket being provided with the slides W, that are connected, by means of the sliding pieces X and links u, 110 to the spring-catches U, and arranged to operate as herein specified.

9. In a hoisting and conveying machine, a traveling carriage, L, provided with a pointed slide, Y, for operating the described mechanism for releasing the bottom sections, S', of the hoisting-bucket, in combination with an adjustable knee-piece, Z, as herein specified. 115

10. The combination, with the traveling carriage L, provided with the segment or wheel l' and spring-latch Q, of the stationary cam-piece Q', arranged to co-operate with the spring-latch Q, as and for the purpose specified. 120

11. The combination, with the traveling carriage L, provided with the segment or wheel l', operated by means of the ropes M and M', and provided with the projecting stud r, of the arm R, rods r¹ and r³, and crank r², and spring-latch g³, all arranged to operate as herein specified. 125
